UNITED STATES PATENT OFFICE.

JAMES M. ZWEIMAN, OF WEST NEW YORK, NEW JERSEY.

COMBINATION LOCK.

1,417,789.

Specification of Letters Patent. Patented May 30, 1922.

Application filed June 22, 1921. Serial No. 479,503.

To all whom it may concern:

Be it known that JAMES M. ZWEIMAN, citizen of Russia (having declared his intentions of becoming a citizen of the United States), residing at West New York, New Jersey, has invented a new and useful Improvement in Combination Locks, of which the following is a specification.

The present invention relates to a new and improved form of combination lock, the construction of which is so designed that the parts thereof may be readily adjusted to operate under different combinations, and a second combination device adapted to co-operate with the lock to permit the operation of the latter and to complicate the combination so as to render it practically impossible to decipher the secret combination and thus open the lock.

The objects of this invention are, first, to provide a double combination lock, of the character hereinafter described in which the secret combinations required to operate the lock may be readily changed without dismantling the entire mechanism; second to provide a series of rotatably mounted disks provided with radially extending spokes and adapted to be independently rotated to receive a selector plate carried by the usual locking bolts to permit the operation of the latter, and third, to provide means for simultaneously effectuating the movement of each set of bolts to release their locking action.

With such objects in view and others which will appear throughout the following description, the invention comprises the novel features and combinations of parts hereinafter fully described and illustratively exemplified in the accompanying drawing, wherein:

Fig. 1 is a substantially longitudinal sectional view taken on lines 1-1 of Fig. 2, showing my improved double combination lock applied to a safe door.

Fig. 2, is an elevational view of the rear of the safe door with the back plate removed to show otherwise hidden parts.

Fig. 3, is a perspective view of the primary combination dial which operates the spoked disks.

Fig. 4, is a front elevational view of the safe door, showing the combination dials.

Fig. 5, is a detail view of one of the spoked wheels, showing the pin replacing one of the

regular spokes and adapted to enter the selector plate to complete one step in forming the combination.

Referring to the drawings, 10 designates a door provided with the usual banked edges 60 11, hinges 12 and fixed bolts 13, the latter of which project from the hinged edge of the door. The rear portion of the door 10 is hollow and provides a chamber 14 in which the operating mechanism is housed. 65 A back plate 15 is secured to the face of back of the door 10 to completely enclose the locking mechanism.

The primary combination device 16 is mounted substantially in the center of the 70 door 10 and comprises a rotatably mounted shaft 17 which extends through the front wall of the door and terminates in a conically shaped dial disk 18. A ring 19 secured to the face of door 10 surrounds the 75 dial and is provided with the usual combination numbers 20. An arrow 21 embossed adjacent the periphery of the dial 18 is provided to register with the numbers 20. The inner end of the shaft 17 carries a guide 80 block 22 having a transverse guideway 23 formed therein. The block 22 is secured to the inner end of the shaft 17 by means of a screw 24. A bar 25 slidably mounted in the guideway 23 is provided with a series of depressions 26 in the outer face thereof and adjacent its forward end; these depressions 26 receive a spring actuated ball 27 carried by the block 22 and operate as a centering 85 or locating device, the function of which 90 will be more fully described hereinafter. The end of the bar 25 opposite to the depressions 26 is provided with a rack 28 having its teeth directed toward the outer side of door 10 and the inner end of this rack 95 28 carries an enlarged tooth 29 which operates a series of spoked disks, referred to hereinafter as selectors.

A fixed spindle 30 surrounds the shaft 17 and is provided at its inner end with a 100 flange 31 which serves as a bearing plate against which the block 22 rotates. Loosely mounted on the spindle 30 and spaced from each other by spacing disks 32 are a series of disks or selectors generally indicated at 105 33, in the present instance four such disks are shown, but it will be understood that any number may be used to provide a more intricate combination. To more clearly describe the operation of the lock the four 110

disks or selectors are designated at 33, 34, 35 and 36 respectively. Radially extending from the periphery of each of these disks 33^a are six evenly spaced spokes 37, one of 5 said spokes being substantially different in cross section from the other five; and, as shown, the oddly shaped spoke comprises a round pin 38, while the other five spokes are rectangular in cross section. It might 10 be noted that the diameters of these round pins 38 are somewhat smaller than the corresponding width of the other spokes 37. The outer ends of these square spokes 37 are provided with threaded openings extending transversely thereof and adapted to receive screws 39 carried by a metal extension generally indicated at 40. Each disk or selector 33^a is provided with one of these extensions 40 which projects outwardly and 15 then rearwardly in the direction of the axis of the spindle 30 to a point which is on a plane even with the tooth 29 and in the path of movement of the latter. The length and lateral outer offset 45 of these extensions will depend upon the position of the disk 33^a to which each is attached, and in 20 Figs. 1 and 3, the relative position of each extension is shown and numbered 41, 42, 43 and 44 respectively. The offset portion 45 25 at the end of each extension 40 is arranged so that its path of rotation with its disk or selector 33^a will be in a circular line which will be of a slightly different diameter than its associate; or in other words, the distance 30 from the axis of the spindle 30 to the offset portion 45 will be greater for each disk beginning with 33, so that when being rotated, the extensions and their offset ends will not be 35 interfered with by the circular movement of 40 each other.

Mounted to rotate in a suitable bearing 46 carried by a bracket 47 which projects from the inner side of the wall of the chamber 14, is a toothed wheel 48, the teeth of 45 which are adapted to mesh with the rack 28. Secured to one face of the wheel 48 is a bevel gear 49 meshing with a second bevel gear 49^a mounted in a suitable bracket and adapted to rotate with a secondary combination shaft 50 which is parallel to the primary shaft 17 and extends through the front portion of the door 10. The outer end of the secondary shaft 50 carries a knob 51 of the usual type employed on safe doors 55 and which knob is provided with an enlarged flange resting against the outer face of the door. This flange indicated at 52 is the secondary combination dial having an arrow 53 registering with suitable numerals 54 on the surface of a ring 55 fixed to the face of the door 10 and surrounding the secondary dial 52. The numerals on the ring 55 correspond with the offset portions 45 of the extensions 40, thus it will be noted 60 that to properly locate the tooth 29 to move

in the path of one of the offset portions 45 it will simply be necessary to rotate the dial 52 which will move the bar 25 axially until the arrow 53 indicates the correct position or number on the dial. This step 70 will, of course, be carried out by the operation of the secondary combination mechanism, which will be more fully described hereinafter.

The bolt shifting mechanism, making up 75 the third mechanical part in the combination of elements comprising this invention, includes three bars or plates 56, 57 and 58 respectively. These plates are provided with outwardly projecting bolts 59 which 80 move in openings 60 formed in three of the side walls of the chamber 14. Plate 56 is positioned at what would be the top of the door and 57 is arranged at the bottom thereof. A stirrup 61 is carried at the back surface of each plate 56 and 57 respectively, and receives the forked end 62 of a slidable rack 63 movable in guideways 64 mounted in the chamber 14. The teeth of these racks 63 mesh with a toothed wheel 65 connected to one face of the bevel gear 49^a and are so arranged that each rack is operated from diametrically opposite sides of the wheel 65, so that a rotation of the wheel 65 will simultaneously move the racks 63 toward or away 90 from the upper and lower edges of the door 10. This operation will set or withdraw the bolts as the case may be, but such a step in the operation may not be effected until the plate 58 is in order to be operated. In Figs. 1 and 2, the construction of plate 58 and its coating parts, are clearly shown, and include an inward projection 66 on the opposite side of the plate from the bolts 59. At the edges of the projection 66 and projecting upwardly at an angle thereof are brackets 67 which support a selector plate 68. This plate 68 extends substantially to the back face of the front of the door 10 and is provided with orifices 69 having a diameter 110 which will just receive the pins 38 and which orifices 69 are spaced so that when all of the pins are aligned in row formation the openings 69 will be axially in register with the pins 38, whereupon the plate 68 may be moved inwardly and over the pins. To effect the inward movement of the plate 68 after the pins 38 are in proper position, the bolt plate 58 is provided with an extension member 70, one end of which is secured to the under face of the projection 66 and the opposite or free end is bent inwardly at right angles and is brought into a plane which is in the path of the extreme outward movement of the bar 25, so that after the combination of the lock has been completed a further turn of the knob 51 will drive the end of the rack 28 against the angular portion of the member 70 to withdraw the plate 58 and also the other bolt plates 56 and 57 130

- respectively in a manner described in the foregoing paragraph. In order to reset the bolts to the locked or extended position a contact boss 71 is provided on the inner end 5 of the projection 66 which will receive the blow from the inner end of the bar 25 opposite to the rack, and tend to again project the bolts of the plate 58 through the openings 60.
- 10 In order to facilitate a change in the working combination of the disks 33^a there is a number on each spoke 37 corresponding with a number on the face of the ring 19 and by changing the extensions 40 from one 15 spoke to another a new combination may be readily provided; it being simply necessary to move the arrow 21 to the number on the ring which corresponds to the number on the spoke having the extension.
- 20 In the operation of the lock, hereinbefore described, it will be assumed that the door 10 has had the bolts extended and the several parts moved to a position shown in Fig. 1, where the bolts are ready to be withdrawn.
- 25 The disk or selector 33 which is nearest to the bar 25 will be the first acted upon principally because it is desirable to work the rack outwardly toward the angular portion of the extension 70. The knob 51 controlling the secondary combination device is rotated in the direction of the arrow *a* in Fig. 4, and the indicator 53 is moved to register with the proper number on the plate or ring 55. In effecting this movement the bevel 30 gears 49 and 49^a rotate with the toothed wheel 48 to move the rack 28 and position the tooth 29 in the path of the offset of the extension 41. The other racks 63 will also be slightly moved, but with no effect because 40 the lost motion or play provided by the arrangement of the stirrups 61 and forks 62 enable all of the disks or selectors to be set before knob 51 may be rotated sufficiently to withdraw the bolts 59. After the first combination number has been properly registered the primary dial 18 may then be rotated, in the direction of the arrow *b*, until the indicator arrow 21, registers with the number indicated on the spoke 37 having 45 the extension member secured thereon. In rotating the dial 18 the shaft 17 and block 22 will likewise turn, whereupon the bar 25 with tooth 29 will move arcuately until the latter engages the offset 45 of the extension 50 41 moving disk or selector 33 and bringing the pin 38 of the disk in register with the first of the orifices 69 in the selector plate 68. The dial 18 is then returned to zero and the knob 51 is again turned to move the 55 tooth 29 in the path of the next offset 45 of the extension 42 carried on the spoke of the disk or selector 34. This operation is repeated until the entire series of disks or 60 65 selectors 33, 34, 35 and 36 are in the position indicated in Fig. 1, whereupon the knob 51
- may be turned to make a complete revolution and bar 25 moved sufficiently to attach the free angular end of the extension 70 moving the latter inwardly to withdraw the bolts on the plate 58 and likewise the upper 70 and lower bolts 59.
- To reset the bolts in locked or extended position the knob 51 is turned in a reverse direction from that just described and the near end of the bar 25 will engage the boss 75 71 as before described.
- It might be added that in order to assure the proper position of the bar 25 throughout its axial movement the spring actuated centering ball 27 moves into the recess or 80 depressions 26 when the tooth 29 is in its registering position, or in other words for each extension 41 there is a depression 26 which will aid in locating the position of the bar 25 by permitting the ball 27 to center in each succeeding depression as the bar 25 is set for a new number.
- I claim:
1. A combination locking device comprising a casing provided with extensible locking bolts, a pair of shafts mounted in said casing, a series of selectors carried by one of said shafts, and means movable transversely of said selectors by the rotation of said other shaft whereby each selector may 90 be engaged and then rotated by said selector shaft to effectuate the movement of said locking bolts.
  2. A combination locking device comprising a casing provided with extensible locking bolts, a pair of dial shafts mounted in said casing, a series of selectors carried by one of said shafts, a selector bar movable transversely of said selector shaft, and means effected by the rotation of the other shaft whereby said bar may be first moved to separately engage each of said selectors and then moved arcuately to rotate said selectors a predetermined distance, so as to permit axial movement of said bolts. 100
  3. A combination locking device comprising a casing provided with extensible locking bolts, one of said bolts having a series of openings therein, a pair of dial shafts mounted in said casing, a series of spoked 105 selectors loosely carried by one of said dial shafts, an extensible bar having a selector engaging projection thereon and mounted transversely of said selector shaft, means operated by said other shaft to move said bar axially whereby said projection may be brought into the path of selectors to rotate each of the latter separately of the other, and means whereby when each selector has been moved to a predetermined position said 115 selectors may be received by said openings in one of the bolts whereby further rotation of the shaft not having the selectors will move the bolts axially and within said casing. 120
  4. A combination locking device comprising 130

- ing a casing provided with extensible locking bolts therein, selector receiving means carried by said bolts, a selector shaft mounted in said casing and including a dial exteriorly of said casing, a series of selectors loosely mounted on said shaft and provided with radially disposed spokes, one of said spokes being of different diameter than the others, and adapted to project through said selector receiving means, a transversely extensible bar carried by said selector shaft and provided with means for engaging said selectors, and a second shaft mounted in said casing and provided with a dial exteriorly of 5 said casing, said second shaft provided with means whereby said bar may be engaged and moved axially following each arcuate movement thereof to bring said projectiton in the path of each succeeding selector so that the 10 latter may be moved a predetermined distance so as to bring each small spoke in register with said selector receiving means whereby further rotatiton of said second shaft will move the bolts axially.
- 15 5. In a lock, a casing having a chamber therein, bolts extensible within and through opposite sides of said casing, a series of spoked disks loosely mounted within said chamber, means for independently rotating each of said disks, means movable with said bolts to receive the spokes of said disks, and means cooperating with said first named means to axially move said bolts.
- 20 6. In a lock, a casing having a chamber therein, bolts extensible within and through opposite sides of said casing, a dial having an inwardly projecting shaft, a series of spoked disks loosely mounted on said shaft, means for rotating each disk independently of the others, means for receiving one spoke of each disk and carried by one of said bolts, a second shaft having a dial exteriorly of said casing, and means carried by said second shaft and cooperating with the bolts where- 25 40 45
- 50 55 60 65 70 75 80 85 90 95 100 105 110 115 120 125 130
7. In a lock, a casing having upright walls, bolts within and through opposite walls of said casing, a pair of dial shafts mounted in said casing, one of said shafts being provided with selector disks loosely mounted thereon, said selector disks comprising central hubs provided with radially dis- posed arms having transverse threaded open- ings therein, projections interchangeable with said arms and arranged so that each disk has one of said projections, the latter 60 extending outwardly in the direction of the arm and then at an angle substantially be- yond the innermost selector disk, one of the arms of each of said disks having its diam- eter smaller than the remaining arms, a plate 65 carried by said bolts and provided with open- ings arranged to register with said small arms, and means whereby when said disks have been moved to bring each of said small arms in register with the openings in said plate the latter may be moyed over said small arms to withdraw and extend said bolts.
8. A bolt locking device of the character comprising extensible bolts mounted on bars within said locking device, a selector shaft having a transversely extensible toothed bar mounted therein, a second shaft mounted in said device and provided with a pinion located in the path of movement of the teeth of said bar, and means carried by one of said bolt bars whereby when the toothed bar is engaged with said pinion rotation of the latter will move the toothed bar axially to engage said means to withdraw and extend said bolts.
9. A bolt locking device of the character described, comprising a casing having out standing walls, bolts extensible within and through opposite sides of said walls, two dials mounted exteriorly of said casing and 90 provided with inwardly projecting shafts, selectors loosely carried by one of said shafts and adapted to be independently rotated, an extensive toothed bar mounted in said selector shaft and provided with means where- 95
- by axial movement of the shaft will engage with one or the other of said selectors, and a toothed pinion operated from the other of said dials and in the path of possible arcuate movement of said tooth bar whereby 100 the latter may be moved axially a predeter- mined distance to bring said engaging means into engagement with anyone of said se- 105
- lectors and upon further movement said pin- 110
- ion is adapted to actuate said bolts to with- draw and extend the latter.
10. In a combination locking device of the character described, the combination of a series of independently rotatable selector disks, a spacing block separating each disk from the other, radiating spokes carried by each disk and comprising rectangularly formed members provided with threaded openings adjacent their free ends, inter- changeable projections adapted to be at- 115
- tached to one spoke of each disk, and means mounted at the inner end of said series of disks adapted to engage said projections to independently rotate said disk a predeter- mined distance.
11. In a combination locking device for safe doors, the combination of a series of selector disks, comprising equally spaced ra- diating arms, one of said arms having its diameter smaller than the remaining arms, 120 125
- the latter provided with openings therein adapted to receive interchangeable exten- sions, one of said extensions being provided for each disk, and an extensible bar carried axially of said series of disks and provided 130

with a projection adapted to be brought into the path of each extension whereby rotary movement of said bar will engage the projection on the latter to independently rotate each of said disks.

12. In a combination lock for doors, the combination of a pair of shafts mounted in said door and provided with dials located exteriorly of said door, graduated rings 10 rounding said dials and provided with indication marks thereon, a series of disks loosely mounted on one of said shafts, a bevel gear keyed to said other shaft, said bevel gear meshing with a second bevel gear having a 15 pinion carried thereby, and an extensible toothed bar mounted in the free end of said disk shaft and adapted to be moved arcuately to engage with said pinion, whereby rotation of said pinion will move said bar 20 axially a predetermined distance indicated by the distance said pinion dial moves with relation to said graduated rings.

13. In a lock, a door casing having its side walls provided with bolt receiving openings, 25 bolts mounted on bars and extensible within and through said openings, stirrups carried on the inner face of said bars, forks movable axially of said bolts and adapted to have one of the legs loosely engaged in said 30 stirrup, and means for moving said forks so as to permit substantial movement in either direction before effecting the movement of said bolt bars.

14. In a lock, a door casing having its 35 side walls provided with an opening, bars movable toward and away from the inner face of said walls and provided with bolts extensible in said openings, stirrups secured to the inner face of each of said bars, 40 forks one leg of which engages over said stirrup and the other leg adapted to abut the outer face of said stirrup, and means for engaging said forks to simultaneously move the latter inwardly and outwardly to withdraw and extend said bolts, said forks being 45 capable of substantial axial movement in either direction before effecting said stirrups.

15. In a lock, a series of selector disks 50 loosely mounted on a common axis, as a center, a selector bar movable transversely of said axis, means whereby said bar may be extended to separately actuate each of said selectors, and means for subsequently moving said bar arcuately to rotate each of said 55 selectors a predetermined distance.

16. In a lock, a series of selector members 60 provided with projections adapted to be independently moved about a common axis as a center, and an extensible member capable of arcuate movement about said axis as a center and provided with a projection, whereby when said extensible member is moved axially the projection may first be 65 brought into engagement with one of said

selector projections and then moved about said axis to rotate said selector a predetermined distance.

17. In a lock, a series of loosely mounted disks having spokes extending radially 70 thereof, one of said spokes of each disk having a different cross section from the remaining spokes, angular extensions carried by one spoke of each disk, means movable in the path of each extension to engage 75 against the latter to move the spokes having the different cross section to a predetermined point, and means for moving said first named means axially to separately engage the extensions of each disk.

18. In a lock, a series of selector disks superposed one on the other, a shaft upon 80 which said disks are loosely mounted, means carried by said shaft for engaging said disks to independently rotate each of the 85 latter to a predetermined position, a locking member for said disks, and means cooperating with said first named means to first, move the latter axially step by step to engage the disks and thereafter to move into engagement with said locking member to lock 90 the said disks against further rotary movement.

19. In a lock, a casing having extensible bolts in opposite walls, said bolts mounted 95 on bars toward and away from each other, stirrups carried on the inner surface of each of said bars, members movable axially of said bolts and provided with a fork at one end thereof adapted to engage said stirrups carried by said bars, the opposite ends 100 of said members being provided with teeth, and a pinion adapted to register with said teeth on each member, whereby rotation of said pinion will first move said members 105 axially of said bolts a substantial distance and then engage said forks with said stirrups to withdraw and extend said bolts.

20. In a lock, a series of loosely rotatably mounted disks having spokes extending 110 radially thereof, one of said spokes of each disk being of a smaller diameter than the remaining spokes, and a bolt plate movable counter to the axis of said disks and provided with openings therein to receive said 115 smaller spokes, whereby said plate may be moved over said small spokes when the latter are prearranged.

21. In a locking mechanism for extensible bolts, an exteriorly mounted dial having a 120 shaft extending inwardly therefrom, selectors loosely mounted on said shaft and provided with radially extending rectangular spokes evenly spaced from each other, a pin carried by each disk to replace one of said 125 spokes, a plate mounted on one of said bolts and provided with an opening therein adapted to receive said pins, a bar mounted transversely of said shaft and provided with a rack on one edge terminating in an en- 130

larged tooth at its inner end, a second dial adjacent said first dial and having a bevel gear carried by its inwardly projecting shaft, a pinion movable with said bevel gear and adapted to engage said rack when the latter is aligned with said pinion, and means carried by said bolt plate, whereby after said second dial has been alternately rotated with said first dial to arrange said pins in alignment with the opening in said plate, to move the latter over said pins to withdraw said bolts by continued rotation of said second dial.

22. In a combination safe locking device, the combination of two dials mounted exteriorly of said safe and each provided with an indicating mark thereon, a divided ring surrounding each of said dials and provided with numerals at each division, selectors

mounted on the axis of one of said dials 20 and provided with spokes having numerals corresponding with those on said ring, interchangeable actuating means carried by one spoke of each selector, and engaging means movable counter to the axis of said selectors 25 and in the path of said actuating means, and means initiated by the rotation of the other dial whereby said engaging means may be moved axially a distance indicated by the relative movement of the indicator on said dial with the numerals on said ring surrounding it to engage each actuating means separately to rotate said selectors a predetermined distance.

In testimony whereof, JAMES M. ZWEIMAN 35 has signed his name to this specification this 21st day of June 1921.

JAMES M. ZWEIMAN.
